UNITED STATES PATENT OFFICE.

JESSE F. McNIEL, OF DOOLEY, VIRGINIA, ASSIGNOR OF ONE-HALF TO
J. E. TRINKLE, OF DOOLEY, VIRGINIA.

MINER'S DINNER-BUCKET.

SPECIFICATION forming part of Letters Patent No. 778,883, dated January 3, 1905.

Application filed September 10, 1904. Serial No. 224,032.

To all whom it may concern:

Be it known that I, JESSE F. McNIEL, a citizen of the United States, residing at Dooley, in the county of Wise and State of Virginia, have invented certain new and useful Improvements in Miners' Dinner-Buckets, of which the following is a full, clear, and exact specification.

This invention relates to articles of manufacture known as "dinner buckets or pails" ordinarily embodying a lamp-chamber at the base and superposed chambers variously arranged for heating the numerous articles comprising the lunch or dinner taken from the home to the place of employment.

The main object of the invention is to provide a dinner-bucket adapted to the needs of miners, where the buckets receive rough usage and the conditions of work involve an atmosphere laden with smoke, dust, and gases, forbidding the employment of a volatile burning fluid.

A further object of the invention is a miner's dinner-bucket that may be made at small expense by unskilled labor in a mountain shop, without the employment of the more or less expensive shaping and beading-rolls, &c., required in the manufacture of such buckets at present known to me.

With these and other objects in view the invention consists in the matters to be described hereinafter in detail, and claimed in the claims at the close of this specification.

In the accompanying drawings, illustrating a miner's dinner-bucket constructed in accordance with my invention, Figure 1 is a view in elevation of a bucket embodying the invention. Fig. 2 is a vertical section of the same, taken on line 2 2 of Fig. 1. Fig. 3 is a top plan of the provision-tray. Fig. 4 is a fragmentary sectional view, and Fig. 5 is a fragmentary sectional view taken on line 5 5 of Fig. 2.

In the manufacture of my miner's lunch-bucket I construct a rectangular body or case A, each side of which is formed of a single flatsheet of tin, the four flat sides being joined

or united throughout their vertical edges by soldered joints to make a water-tight case. From this construction it will be seen that no 50 curving of the four sheets is required, the meeting or vertical edges being united by a simple solder joint or they may be lock-seamed and soldered, an operation requiring no apparatus save the ordinary tinners' tools universally employed in country shops where fine or elaborate work is not required.

Somewhat above the lower end of the body or case A a bottom B is permanently secured, the joints between the bottom and the vertical walls or sides of the case being made moisture-proof or non-leakable in a manner well known in the art and not necessary to describe.

A non-leaking vessel or tray C of less cross-sectional area than the case A is removably seated therein, its bottom resting upon brackets a, located at a distance above the bottom B to afford space for liquids—such as coffee, tea, &c.—which may form a part of the lunch or dinner of the miner. This vessel or tray 70 C is designed to contain the food carried by the miner for his lunch or dinner and is divided by partitions c and c' into compartments c², c³, and c⁴ to receive meats, vegetables, bread, and pastry or such articles as the appetite of the miner requires. As shown, the compartment c² is designed to receive meat and vegetables which contain moisture, and the smaller compartments c³ and c⁴ are intended for bread, pastry, and the like, which deteriorate as palatable foods when rendered moist by absorption of moisture from other foods.

Above the tray C and resting snugly upon the partitions c and c' is a cover D, shaped 85 and of a size to fit snugly within the case A, and as the partitions are slightly higher than the vertical walls of the tray it is apparent that vapor rising from the compartment c² will not pass into the compartments c³ and c⁴. 90 This cover is provided at a suitable point centrally, as here shown, with an upright vent-tube E, the lower end of which communicates with the three compartments of the tray c²,

c^3 , and c^4 , thus affording ventilation through the single tube to the several compartments of the tray. The vent-tube is preferably closed by a perforated cap c , which permits emission 5 of vapors rising from the case or the tray, but prevents ingress of coal-dust or other undesirable matter.

The vessel or case A is closed at top by a cap F, formed of a flat metal sheet crimped at 10 its edges to form a flange f to overhang the top edge of the case, and a depending flange f' , fitting not quite snugly within the top of the case. This cap is provided at a proper point centrally, as shown, with an opening f^2 , 15 through which the vent-tube E of the cover D protrudes, and the depending flange is of a height to rest upon the margins of the cover and sustain the flange f slightly above the top edge of the case. The case is fitted at diametrically opposite sides with ears A' bent 20 outward and inward at approximately right angles, thus constituting keepers to engage and hold the overhung flange f of the cap. To the upper end of the ears are pivoted the opposite ends of a bail G, proportioned with respect to the cap to permit the passage of the arm of a man, whereby the bucket may be carried on the arm and the hands left free.

A bottom H is removably secured to the 30 lower end of the case by means of right-angled hinge-pintles h , which may be slipped into and out of loops or eyes d' , secured to the wall of the case, said bottom H being provided on its opposite edge margin with a strap 35 or latch h' , adapted to engage a stud or keeper a^2 , projecting from the wall of the case. A stop h^2 is provided to prevent the removable bottom from being slid out of hinged position when in a closed condition. The removable 40 bottom when used is designed to hold a lamp I (which may be an ordinary miner's lamp) and forms the bottom wall of a lamp or heating chamber J, the other walls of which comprise the side walls of the case and the fixed 45 bottom or partition B. The side walls of the heating or lamp chamber are perforated near the lower margin, as at a^4 , to admit air needed to support combustion, and a smoke-vent a^3 is provided near the top of the chamber to carry 50 off the unconsumed products of combustion and promote circulation of air in the chamber.

A compartment K is formed between the cover D and cap F, which may be conveniently used to carry packages of sugar, salt, 55 &c., since moisture is excluded from this compartment, due to the construction described.

In use coffee, tea, or other desired liquid will be poured into the vessel upon the fixed bottom B and food stored in the compartments of the tray C, which will then be inserted in the vessel, resting on the brackets a^4 above the coffee, as will be understood, the cover D having now been inserted and

resting on the partitions of the tray and the cap F put in place to close the top of the vessel or bucket. Heat being now introduced 65 into the heating-chamber J, the coffee will be heated and in turn impart heat to the tray above it, thus warming the contents thereof. Steam rising from the coffee will ascend between the walls of the tray and bucket, passing 70 beneath the cover D and above the compartments of the tray to the central vent-tube E and escape thence to the atmosphere. Should any steam from the coffee pass between the 75 edges of the cover D and the walls of the bucket, it finds ready escape between the top edge of the latter and the overhanging flange of the cap F.

Tin or other serviceable cups, together with 80 knives, forks, &c., may be carried in the heating-chamber J or elsewhere, the compartment K being well adapted for such small articles as mentioned, which will not interfere with the packages of salt, sugar, &c., which 85 may be carried therein.

While it is designed that the bucket be heated by a miner's or other lamp preferably burning lard-oil, it will be seen that the removable bottom H may be taken off and the 90 bucket placed above a bed of live coals, or other sources of heat may be employed in the same manner.

Having thus fully described my invention, what I claim as new, and desire to secure by 95 Letters Patent, of the United States, is—

1. A miner's dinner-bucket consisting of a case having a fixed bottom above its lower end, a removable-compartment tray supported above the bottom by brackets projecting 100 from the walls of the case, a removable cover snugly fitting the case and supported on the partitions of the tray and having a single vent-tube communicating with the several compartments of the tray, and a cap having outward and depending flanges and an opening 105 to receive the vent-tube of the cover, substantially as described.

2. A miner's dinner-bucket consisting of a case having a fixed bottom above its lower end, a removable-compartment tray supported above the bottom by brackets projecting from the walls of the case, a removable cover snugly fitting the case and supported on the partitions of the tray and having a single 115 vent-tube communicating with the several compartments of the tray, a cap having outward and depending flanges and an opening to receive the vent-tube of the cover, and a hinged bottom to close the lower end of the 120 case, substantially as described.

3. A miner's dinner-bucket consisting of a case having a fixed bottom above its lower end, a removable-compartment tray supported above the bottom by brackets projecting 125 from the walls of the case, a removable cover

snugly fitting the case and supported on the partitions of the tray and having a single vent-tube communicating with the several compartments of the tray, a cap having outward and depending flanges and an opening to receive the vent-tube of the cover, and a removable hinged bottom to close the lower end of the case, substantially as described.

In testimony whereof I have signed my name to this specification in the presence of two subscribing witnesses.

JESSE F. McNIEL.
